E. W. KRUSE

RESERVE SUPPLY DEVICE FOR GASOLINE TANKS

Filed Dec. 14, 1925

UNITED STATES PATENT OFFICE.

EDWARD W. KRUSE, OF CHICAGO, ILLINOIS.

RESERVE-SUPPLY DEVICE FOR GASOLINE TANKS.

Application filed December 14, 1925. Serial No. 75,175.

This invention relates to a class of devices quite extensively used on gasoline tanks for maintaining, during normal running, a reserve supply of gasoline in the tank to notify the driver of the car when the supply is running low, and afford him sufficient gasoline to reach the nearest filling station after he has been notified, by the stoppage of the motor through lack of fuel, that his gas tank 10 needs replenishment.

One object of the present invention is to provide a simple and inexpensive accessory for maintaining a reserve supply in the tank which may be readily applied to the supply 15 line from the tank to the carburetor in all installations using a gravity flow. Another object is to provide such a device wherein a single valve may perform the three-fold function of, first, maintaining the reserve 20 supply of gasoline intact during normal running, second, bringing into use the reserve supply when required, and, third, cutting off the gas line to the carburetor and facilitating the locking thereof in cut-off position, 25 this latter being in the nature of an anti-theft provision.

Other objects and attendant advantages of the invention will be apparent to persons skilled in the art as the same becomes better 30 understood by reference to the following detailed description, taken in connection with the accompanying drawings wherein I have illustrated one practical and approved embodiment of the principle of the invention, 35 and in which—

Fig. 1 is an elevation of a fragment of a gasoline tank, a known form of sediment trap and drain connected to the bottom of the tank, and my improved reserve supply 40 device connected in between the sediment trap and the flow line to the carburetor;

Fig. 2 is an enlarged view of the sediment trap and reserve supply device viewed from the right of Fig. 1, and showing the valve in 45 cut-off position, with a lock, indicated in dotted lines, applied to the valve handle;

Fig. 3 is a vertical section through the valve and associated leveling device, on the line 3—3 of Fig. 2, the valve appearing in 50 cut-off position;

Fig. 4 is a vertical section in a plane at right angles to that of Fig. 3 on the line 4—4 of Fig. 3;

Fig. 5 is a fragmentary sectional view 55 showing the valve in normal running posi-

tion wherein the reserve supply is maintained intact;

Fig. 6 is a view similar to Fig. 5 showing the valve shifted a half turn to effect the flow of the reserve supply; 60

Fig. 7 is a fragmentary view showing the position of the valve handle corresponding to the normal running position shown in Fig. 5; and

Fig. 8 is a fragmentary view showing the 65 position of the valve handle when running on the reserve, corresponding to Fig. 6.

Referring to the drawings, at 10 is indicated a fragment of a gasoline tank of the type commonly mounted in front of the dash 70 and below the deck or hood of an automobile and supplying gasoline to the carburetor by gravity flow; a familiar type of such tank being that employed on the latest models of the well-known Ford car. Connected into the bottom of the tank, as by a threaded joint 11, is a combined elbow and sediment trap 12, this member as herein shown, copying the device now used on the Ford car. This member is equipped with a cock 13 for 75 turning the gasoline on and off, and on the upper portion of the sediment bulb is an internally tapped boss 14 which, in standard practice, receives an elbow (not shown) connecting it with the pipe line to the carburetor. In applying the device of the present invention, this elbow is discarded, and replaced by the improved level controlling 80 valve next to be described.

15 designates as an entirety a casting, 80 through which is formed a tapered bore 16 (Fig. 3) that constitutes a seat for a rotary three-way valve body 17. On one side of the casting is a horizontal threaded nipple 18 (Fig. 4) which screws into the tapped 85 boss 14 and forms a support for the casting. On the lower end of the casting is a vertical threaded nipple 19 to which the gasoline flow pipe 20 is united, as by a nut 21 (Fig. 2). A horizontal duct 22 through the nipple 18 and the body of the casting opens at its inner end through the valve seat 16. A vertical duct 23 through the nipple 19 and the body of the casting opens at its upper or inner end through the valve seat 16 in 100 the same vertical plane as the duct 22. Another vertical duct 24, in line with the vertical duct 23, opens at its lower end through the valve seat 16 and at its upper end into a tapped recess or socket 25 in the top of the 105 casting. The duct 23 is closed at its upper end by a stopper 26, and the duct 24 is closed at its lower end by a stopper 27. The casting is closed at its upper 110 end by a stopper 28.

casting 15. An oblique duct 26 in the casting 15 connects the duct 22 with the recess 25.

Fit into the vertical duct 24 is a pipe 27 which extends above the top of the casting 15 to a point sufficiently above the bottom of the gasoline tank to normally maintain a liquid level in the latter which will afford a reserve of approximately a gallon of gasoline in the tank. Surrounding the pipe 27 and at its lower end screwed into the tapped socket 25 is a larger pipe 28 closed at its upper end by a wall 29 on which is formed a threaded nipple 30, the wall 29 and nipple 30 being slightly elevated above the top of the leveling pipe 27. The nipple 30 is formed with a minute longitudinal duct or passage 31, and to said nipple is attached in a liquid-tight manner the lower end of a siphon breaker pipe 32 which extends upwardly to or above the maximum liquid level of the tank 10. A simple connection of the pipe 32 to the nipple 30 may be made in a manner shown in Fig. 4, wherein it will be seen that the lower end of the pipe is swaged outwardly to fit over the conical upper end of the nipple, and the swaged portion is drawn into tight contact with the nipple by a clamp nut 33. The valve 17 is drawn into tight engagement with its seat by the well-known device of a thrust spring 34 encircling a reduced extension 17' of the valve, and abutment washers 35 and 36, the former abutting against the side of the casting around the end of the valve seat and the latter abutting against a cotter pin 37.

The three-way valve body 17 is formed with a diametric duct or way 38, and with a branch duct or way 39 at right angles to the duct 38 between the latter and the periphery of the valve body.

The other or wide end of the valve body projects beyond the valve casing and is formed with a diametric slot 40 in which is pivoted, on a pin 41, the inner end of a valve handle 42. This valve handle is preferably formed as a flat strip having its radially projecting portion or handle proper warped through an angle of ninety degrees so as to present two flat sides lying in planes transverse to the axis of the valve when the handle is in any of its working positions. As shown in Figs. 7 and 8, one side of the handle may be blank, and the other may carry the letters RES., or other symbol to indicate that when the same is displayed to view the reserve supply is being used.

In normal operation, the valve occupies the position shown in Fig. 5, and the handle is in the pendant position illustrated in Fig. 7 with the blank side showing. Assuming that the gasoline tank is full, the liquid flows through the oblique duct 26 into the

annular space between the pipes 27 and 28, rising through the nipple duct 31 and the siphon breaker pipe 32 to the level of the liquid in the tank. At the same time, the gasoline is free to flow downwardly through the pipe 27, valve duct 38 and nipple duct 33 to and through the supply line 20; and this condition will continue until the level in the tank falls to the level of the top of the siphon pipe 27, at which point it will cease to flow, thereby notifying the driver that the gas supply is low. Thereupon the driver will swing the handle 42 on its pivot upwardly to a position above the valve, and will then turn the handle to the right through a half circle, bringing it to the position indicated in Fig. 8. This shifts the valve through 180° to the position shown in Fig. 6, wherein the reserve supply of gasoline in the tank is free to flow through the nipple duct 22 and valve ducts 38 and 39 into the lower nipple duct 23 and thence to the supply line 20. As soon as the tank has been replenished, the valve handle will again be swung upwardly and then through a half turn to the right, restoring it to the position shown in Fig. 7.

The purpose of providing the relatively fine nipple duct 31 in the siphon breaker line is to prevent loss of gasoline by jolting from the upper end of the siphon breaker pipe 32, and avoid the necessity of extending the latter pipe to an undue height. I have found by experiment that, unless the siphon breaker line is partially throttled at some point, considerable gasoline is jolted out and wasted from the upper end of the siphon breaker.

To economize space in the transverse dimensions of the valve casing, the lower end of the outer pipe 28 may be beveled, as indicated in Figs. 4, 5 and 6, to provide greater clearance for the flow of the gasoline through the upper end of the duct 26.

When the driver has occasion to leave the car standing unguarded, the gasoline supply line may be cut off by turning the handle 42 to the horizontal position shown in Fig. 2 wherein it lies alongside the nipple 18, and the handle may be locked to the latter by an ordinary padlock 43 indicated in dotted lines. The position of the valve corresponding to this position of the handle is shown in Fig. 4, wherein it will be seen that the nipple duct 23 constituting part of the flow line to the carburetor is occluded by the solid side of the valve.

With the present attachment the regular cut-off valve 13 is not necessary, but, if retained will, of course, be left continuously open.

While I have herein shown and described one practical embodiment of the invention which, in actual service, has been found to satisfactorily effectuate the stated purposes

and objects thereof, it is manifest that the structural features shown and described may be variously modified without departing from the substance of the invention or sacrificing any of the advantages thereof. Hence I do not limit the invention to the details disclosed, but reserve such variations and modifications as fall within the spirit and purview of the appended claims.

10 I claim—

1. A reserve supply attachment for oil tanks, comprising a valve housing containing a circular valve seat, high and low flow passages both opening into said valve seat through ports located ninety degrees apart, and a discharge passage from said valve seat, a rotary three-way valve fitted to said seat controlling the flow through said passages and ports and operative in one position thereof to cut off said discharge passage from both said high and low flow passages, a siphon breaker communicating with said high flow passage, and a handle pivoted to one end of said valve to swing in a plane of the axis of said valve whereby either side of said handle may be brought into view from a point opposite one end of said valve.

2. The combination with a gasoline tank, and a supply pipe coupling connected into and communicating with the lower portion of said tank, of a valve casting formed with a lateral nipple adapted for connection to said coupling, a discharge nipple adapted for connection to the supply pipe, a valve seat ported for communication with both said nipples, a vertical duct between its upper end and said valve seat, and an oblique duct between its upper end and the bore of said lateral nipple, an inner pipe registering

40 at its lower end with said vertical duct and having an open upper end located above the level of the bottom of said tank, an outer pipe mounted on the upper end of said casting around said first named pipe and forming with the latter an annular flow passage 45 with which the upper end of said oblique duct communicates, a valve fitted to said valve seat and formed with ducts controlling the flow through said nipples and valve casting ducts, and a siphon breaker pipe connected to the top of said outer pipe and extending to the level of the top of said tank.

50 3. A specific form of claim 2, wherein the said outer pipe is formed on its upper end with a nipple having a minute bore, and said siphon breaker pipe is attached to said nipple, whereby splashing of gasoline in said siphon breaker pipe is checked.

55 4. A specific form of claim 2, wherein said valve and valve seat are circular in cross-section, and said valve is rotatable in said valve seat between three positions, in one of which it causes an up and down flow through said oblique duct, annular flow passage and inner pipe to the discharge nipple, in another of which it causes a direct flow 60 from said lateral nipple to said discharge nipple, and in the third of which it cuts off the flow through said discharge nipple.

65 5. In combination with the subject-matter 70 of claim 2, a handle so mounted on said valve that when the latter has been turned to cut off the flow through the discharge nipple, said handle will lie alongside of and substantially parallel with one of said nipples 75 whereby it may be locked to the latter.

EDWARD W. KRUSE.
